(57) **CLAIM**

I claim the ornamental design for the overhead light fixture, as shown and described.

DESCRIPTION

FIG. 1 is a perspective view of an overhead light fixture; FIG. 2 is a side view of an overhead light fixture; FIG. 3 is a back view of an overhead light fixture; and, FIG. 4 is a bottom view of an overhead light fixture. The broken lines shown on the drawings depict portions of the overhead light fixture that form no part of the claimed design.
